GRAIN CAR DOOR

Filed Feb. 18, 1927

FIG. 2

Inventor
R.F. White
by *Fatherbaugh Co.*
Attns.

UNITED STATES PATENT OFFICE

RONALD FRASER WHITE, OF MIDLAND, ONTARIO, CANADA

GRAIN-CAR DOOR

Application filed February 18, 1927. Serial No. 169,288.

My invention relates to improvements in grain car doors, and the object of the invention is to so construct the doors that the grain discharge orifice may be located centrally of the door and of maximum capacity, and at the same time reinforce the bottom edge of the door so that it will be grain tight and it consists essentially of the arrangement and construction of parts as hereinafter more particularly explained.

Fig. 1 is a front elevation of my door.

Fig. 2 is a horizontal section showing my door in place between two verticals forming the door opening of a grain car.

Fig. 3 is a vertical section on line 3—3 Figure 1.

Fig. 4 is a vertical section on line 4—4 Figure 1.

In the drawing like characters of reference indicate corresponding parts in each figure.

1 and 2 indicate two verticals forming the side posts of the door of a grain car. 3 indicates the body of my door provided on its outer face with two verticals 4 and 5 which when the door is in place bear against the inner faces of the side posts 1 and 2. 6 and 7 are verticals located intermediately between the verticals 4 and 5 and equi-distant on each side of the centre of the door body 3. 8 is a discharge opening formed in the door body in proximity to the bottom thereof. 9 is a spacing piece extending between the verticals 6 and 7, and 10 and 11 are spacing pieces which extend between the verticals 4 and 6 on one side of the door and 5 and 7 on the opposite side.

12 is an angle bar which is secured to the lower ends of the verticals 4, 6, 7 and 5 by the bolts 12^x extending through each vertical and the vertical flange of the angle bar. The horizontal flange of the angle bar extends beneath the lower ends of the verticals 4, 6, 7 and 5 and the spacing pieces 9, 10, 11, thereby reinforcing the whole lower end of the door between the side posts 1 and 2 of the car between which the body of the door fits.

10^x is a bar extending between the outer verticals 4 and 5 and against which the upper ends of the verticals 6 and 7 bear.

14 and 15 are securing plates connecting

the upper ends of the verticals 6 and 7 to the bar 10^x. 15 is a plate provided with a segmental spherical orifice 16. The plate 15 is secured to the door body by means of the bolts 17 and the verticals 6 and 7 and spacing piece 9 which overlaps the edges of the plate to hold it in position.

18 is a segmental spherical plate which is swung upon a bolt 17 and is inserted between the plate 15 and the door body so as to form a cover for the discharge opening 8. The plate 18 is provided with a pin 19 by which it may be manually swung upon the central bolt 17 so as to assume an inverted position to open the discharge opening 8 to permit the grain to be discharged.

When it is desired to close the discharge orifice the plate 18 is swung to the position shown in the drawing, the pin 19 being engaged by a latch 20 holding the plate in a locked and closed position.

The door is held between side posts 1 and 2 of the car by any suitable locking devices such as indicated at 21, consisting of a plurality of levers 22 swung upon bolts 23 and provided with ratchet teeth 24 adapted to be forced into the wood forming the side posts 1 and 2 of the car door so as to lock the door firmly in place.

What I claim as my invention is:

The combination with a grain car of a door having a segmental orifice approaching a semi-circle, a pivot bolt extending through the door concentric to the centre of the orifice, a plate swung centrally upon the bolt forming a closure for the orifice, a frame plate conforming to the shape of the orifice and overlapping the edge thereof, securing bolts extending through the frame plate and door clear of the cover plate, a handle extending outward from the cover plate, a gravity latch swung upon the frame plate and adapted to automatically engage the handle when the cover plate is brought to the closed position to lock the cover plate in such position.

RONALD F. WHITE.
